UNITED STATES PATENT OFFICE

169,578

PSYCHIATRIC TESTING AND DEMONSTRATION DEVICE OR SIMILAR ARTICLE

Kenneth K. Buzby, Medford Lakes, N. J.

Application July 11, 1952, Serial No. 20,572

Term of patent 14 years

(Cl. D25—1)

To all whom it may concern:

Be it known that I, Kenneth K. Buzby, a citizen of the United States of America, residing in Medford Lakes, county of Burlington, State of New Jersey, have invented a new, original, and ornamental Design for a Psychiatric Testing and Demonstration Device or Similar Article, of which the following is a specification, reference being had to the accompanying drawing forming part thereof, wherein:

The drawing is a perspective view of a psychiatric testing and demonstration device or similar article showing my new design.

In the drawing, the shading on the discs and globe is intended to indicate that said parts are transparent.

I claim:

The ornamental design for a psychiatric testing and demonstration device or similar article, as shown and described.

KENNETH K. BUZBY.
